BEVERAGE-DISPENSING APPARATUS

Lewis Diamond, Pittsburgh, Pa.

Application January 27, 1933. Serial No. 653,765

5 Claims. (Cl. 225—1)

This invention relates to beverage-dispensing apparatus.

The object of the invention is to provide compact, self-contained, beverage-dispensing apparatus of such arrangement that it may be readily transported from place to place, and is formed with various elements, and subcombinations of elements, in the structure which may be readily removed from the remainder of the apparatus.

10 The beverage-dispensing apparatus is complete in that it provides space for the reception of a beverage-containing receptacle with means for applying gas pressure to said receptacle, a counter surface, and a surface for supporting drinking vessels arranged with and beneath the counter surface, together with a structure comprising a receptacle containing a cooling coil, and a bosh or sink formed as a unit structure with the cooling coil receptacle, so that the cooling coil and bosh 20 structure is removable as a unit from the frame or cabinet of the apparatus.

A further object of my invention is to provide a beverage-dispensing apparatus which is neat and sightly, from whatever side it may be viewed, 25 and which may be readily shifted to various positions on a floor.

In the accompanying drawings Figure I is a plan view of my beverage-dispensing apparatus; Figure II is a rear elevation thereof; Figure III is 30 a fragmentary cross-sectional view, looking in the direction of the arrows, taken on the line III—III of Figure II; Figure IV is a plan view of the surface for receiving drinking vessels, or workboard, of the apparatus; Figure V is an edge view of the 35 workboard; Figure VI is a plan view of the cooling coil and bosh assembly; and Figure VII is a side elevation of the cooling coil and bosh assembly indicating the assembly as mounted in the frame or cabinet of the apparatus.

40 In the accompanying drawings reference numeral 1 designates the side walls of the frame or cabinet structure of the apparatus, and reference numeral 2 designates the front wall of the cabinet. A cover, or counter member, 3 is formed and dimensioned to rest upon the side walls 1 and 45 front wall 2 of the cabinet, and has a depending lip or flange 4 arranged to lie outwardly of the front and side walls 1 and 2 to hold the cover in position on the front and side walls.

50 The interior of the cabinet is divided into compartments by a transverse wall 5. In the compartment 6, shown to the right in Figures I and II of the drawings, is mounted the coil box and bosh assembly designated generally by reference 55 numeral 7. This assembly comprises a metal box

or casing 8 arranged to rest on cleats 9 formed interiorly of the compartment. Within the coil box is a coil 10 terminating at the rearward or operating face of the box in a draw-off spigot 12. Carried on rearward or operating face of coil 60 box 8 is a bosh 13, extending rearwardly and beneath a spigot 12. A second spigot 14 is also carried by the rearward or operating face of the coil box, and may be suitably connected to provide fresh rinsing water. It is understood that coil 65 box 8 is to be packed with ice around coil 10. A drain connection 15 for the coil box communicates with a drain 16 from the bosh. A drain pan 17 may be disposed in compartment 6 beneath drain 16. The provision of a drain pan is desirable in order that connection need not be made to a permanent drain.

In the other compartment 18 of the cabinet, shown to the left in Figures I and II, is a barrel-holding structure comprising a platform 19 and 75 rear door 20. At the inner end of platform 19 are casters 19a, and the rear wall 20 is provided with a leg or legs 21 carrying casters 21a. Platform 19 may thus be drawn out for replacement of the beverage-containing keg or barrel 22, and the gas 80 cylinder 23 connected with the barrel. As shown, barrel 22 has a suitable connection 24 with cooling coil 10.

Underlying the cover, or counter, 3 is a workboard 25, having a portion 25a extending rearwardly beyond the counter. Workboard 25 is desirably covered with corrugated sheet metal, as shown, and serves as a surface upon which drinking vessels may be placed, while the space between the workboard and the under face of the 90 counter provides for the neat stowage of the drinking vessels. Workboard 25 is supported in position by stringer 11 of the cabinet structure, and by a cleat 26 on the interior surface of front wall 2 of the cabinet. At the end of workboard 95 25 which lies adjacent the bosh and coil box the board is provided with a hooked extension 25b, which lies upon and engages a wall member or support 13a extending upwardly from the bosh. This extension 25b of the workboard permits it to 100 drain into the bosh 13.

It should be understood that both the coil box compartment 6, and the barrel compartment 18, are provided with floors 29 and 30, upon which drain pan 17 lies, and on which barrel-supporting platform 19 is mounted. In connection with the barrel-supporting structure, it may be noted that leg 21, or its equivalent, compensates for the difference in level between cabinet floor 29 and the 105 surface on which the apparatus as a whole is 110

mounted, so that the barrel-supported structure may be moved straight out from the cabinet.

The entire beverage-dispensing apparatus, or "bar" may be mounted upon casters 27, so that it may be readily shifted from place to place. It will be noted that the structure as a whole is self-contained and is compact, thus being well adapted to installation in stores, restaurants or homes. It is also particularly useful for use at fair grounds, carnivals and the like. The arrangement is such that all the equipment necessary for the stowage and delivery of a carbonated beverage, such as beer, is contained within a remarkably small compass. The arrangement is such that in this self-contained unit everything necessary for the dispenser, or bar man, is most conveniently arranged. With the gas cylinder 23 and drain pan 17 housed in the cabinet, no connections outside the structure need be made for gas or drainage. Desirably a small water tank is also provided in the region of the coil box lying upwardly of the cooling coil 10 to provide a supply of rinsing water within the structure for water spigot 14.

For transportation from place to place, and particularly for use on excursions and picnics, the structure may be readily disassembled and may be readily reassembled at the place of its use. The cover or counter 3 is readily lifted from the walls of the cabinet, and the barrel-carrying structure and the workboard are also readily removable. The assembly of coil box and bosh is also readily removable as a unit from the structure. In order to remove the coil box and bosh assembly, it is necessary merely to disconnect cooling coil 10 from the line 24 which places it in communication with a keg. Workboard 25 is then lifted from its position engaging the upper extension of the bosh. The coil box is attached to transverse partition 5, as will be seen in Figure II, by means of a plurality of screws 28. With coil 10 disconnected, and workboard 25 removed, it is merely necessary to take out the screws 28 in order that the entire coil box and bosh assembly may be lifted from the cabinet.

As a unit my dispensing apparatus is particularly sightly, because of its compactness. Because of the position of the workboard providing stowage for drinking vessels under the counter, and the barrel-supporting structure providing a smooth rear door to hide the keg or barrel and gas cylinder, and because of the neat coil box and bosh structure, my apparatus is sightly from the rear as well as from the front. It is, therefore, suitable for use in large spaces such as an assembly hall, or ball room, in which it might be moved from place to place, and necessarily viewed from the rear as well as from the front and sides.

If it is desired to incorporate one or more of the dispensing units in a long bar, the cover 3 may be removed, and a longer cover, made to rest upon one or more dispensing units may replace the simple unit cover shown.

I claim as my invention:

1. Self-contained apparatus for dispensing beverages in chilled condition comprising a cabinet having side and end walls and a cover or counter, and beverage-dispensing elements prop-

er wholly contained by said cabinet; said dispensing elements proper comprising a barrel-supporting structure housable in said cabinet and mounted for withdrawal therefrom, a door on said barrel-supporting structure arranged to conceal a barrel thereon as viewed from the rear, a workboard below the counter and at least partially underlying the counter providing a supporting surface for drinking vessels and with the cover providing a stowage compartment for drinking vessels, and a unit structure comprising a coil box and bosh mounted in the cabinet to one side of the barrel-supporting structure and removable as a unit from the cabinet. 80 85

2. Self-contained apparatus for dispensing beverages in chilled condition comprising a cabinet having side and front walls, a cover or counter, said cabinet arranged to provide a chamber for a bulk container of beverage, and beverage-dispensing elements proper wholly contained by said cabinet; said dispensing elements proper comprising a workboard below the counter and at least partially underlying the counter providing a supporting surface for drinking vessels and with the cover providing a stowage compartment for drinking vessels, and a unit structure comprising a coil box and bosh mounted in the cabinet to one side of the barrel-containing chamber and removable as a unit from the cabinet. 90 95 100

3. Self-contained apparatus for dispensing beverages in chilled condition comprising a cabinet having side and front walls, said cabinet arranged to provide a chamber for a bulk container of beverage, and beverage-dispensing elements proper wholly contained by said cabinet; said dispensing elements proper comprising a unit structure comprising a coil box and bosh mounted in the cabinet to one side of the beverage-containing chamber and removable as a unit 110 115 from the cabinet, and a workboard providing a supporting surface for drinking vessels mounted in the cabinet and arranged to drain into the bosh. 120

4. Self-contained apparatus for dispensing beverages in chilled condition comprising a cabinet having side and end walls, and beverage-dispensing elements proper wholly contained by said cabinet; said dispensing elements proper comprising a barrel-supporting structure housable in said cabinet and mounted for withdrawal therefrom, a unit structure comprising a coil box and bosh mounted in the cabinet to one side of the barrel-supporting structure and removable as a unit from the cabinet, and a workboard providing a supporting surface for drinking vessels mounted in the cabinet and arranged to drain into the bosh. 125 130 135

5. In beverage dispensing apparatus the combination of a cabinet comprising a front wall, at least one side wall and a cover or counter, with an assembly structure of coil-box and bosh arranged for insertion into and removal from the cabinet as a unitary structure, supporting means for said coil-box and bosh assembly in the cabinet beneath the cover or counter member thereof, and a drain board supported in the cabinet and arranged to drain into the bosh. 140
